CLAIM

I claim the ornamental design of a sill plate, as shown and described.

DESCRIPTION

FIG. 1 is a perspective view of the sill plate showing my new design, shown broken in the center with a double line to indicate that no particular length is claimed.

FIG. 2 is a front elevation thereof.

FIG. 3 is a rear elevation thereof.

FIG. 4 is a side elevation views thereof. The right and left sides of the sill plate are identical.

FIG. 5 is a top plan view thereof; and,

FIG. 6 is a bottom plan view thereof.
